[57] CLAIM

The ornamental design for an adjustable needlework frame, as shown and described.

DESCRIPTION

FIG. 1 is a front elevational view of an adjustable needlework frame showing my design in a selected position of adjustment;

FIG. 2 is a top plan view thereof;

FIG. 3 is a side elevational view thereof;

FIG. 4 is a rear elevational view thereof;

FIG. 5 is a bottom view thereof; and
FIG. 6 is a sectional view as seen from a plane indicated by the line 6—6 of FIG. 1.
